UNITED STATES PATENT OFFICE.

CHARLES FREDERIC AINSWORTH, OF HORWICH, AND SYLVANUS ANDERTON, OF BOLTON, ENGLAND.

COMBING-MACHINE.

SPECIFICATION forming part of Letters Patent No. 734,652, dated July 28, 1903.

Application filed July 9, 1902. Serial No. 114,915. (No model.)

To all whom it may concern:

Be it known that we, CHARLES FREDERIC AINSWORTH, a resident of Lower Brazley, Horwich, and SYLVANUS ANDERTON, a resident of No. 18 Henry street, Bolton, in the county of Lancaster, England, subjects of the King of Great Britain, have invented certain new and useful Improvements in Combing-Machines, of which the following description is a specification.

Our invention relates to combing-machines for the treatment of fibrous substances of the class well known as of and usually styled the "Heilman" type, wherein a rotary cylinder carrying combing-needles is mounted to operate in contiguity and conjunction with nipper-jaws which retain or hold the fibrous substances while being acted upon by said needles, said jaws being usually styled the "nipper-knife" and "cushion-plate."

As is well known, the nipper-knife is constructed with a flange called the "lip," which projects beyond it to force or carry the fibrous substances into contact with or into the path of motion of the needles on the rotary cylinder for purposes well understood, and it is to the formation and construction of this lip that our invention applies.

In the adjustment or setting of the nipper-knife as heretofore constructed it has been found necessary to allow sufficient space between the edge of its lip and the path of motion of the needles' points to enable these latter to pass or travel clear of the same without actually being brought into contact with it under any circumstances; otherwise said points would be damaged and rendered unfit for service. To obviate this and provide means whereby we are enabled to adjust or set the nipper-knife considerably closer to the path of motion of the needles' points, and that without endangering their efficiency, thus enabling said needles to operate upon a greater quantity or thickness of material, is the object of our present invention. This object we attain by making use of the devices and following the method of constructing same, as hereinafter described, and as illustrated in the accompanying sheets of drawings, where-

50 in—

Figure 1 is a sectional elevation of a suffi-

cient part or portion of a combing-machine to show the application thereto of our invention. Figs. 2 and 3 are front and back views of a nipper-knife, upon a smaller scale than Fig. 1, constructed in accordance with our invention. Fig. 4 is an end elevation, upon the scale of Fig. 1, of the knife illustrated by Figs. 2 and 3.

In carrying our invention into effect we form the lip *a* of the nipper-knife *b* so that we may cover its lower edge with leather *c* or with other substance of a similar nature that will attain the same result in order that provided by any means or reason should any of the points of the needles *d* on the cylinder *f* be brought into contact with such substance *c* they will be able to pierce or cut through the same without being damaged or rendered unfit to perform the functions desired of them. Thus we are enabled more closely to press the laps or slivers of fibers passing beneath these lips *a* down upon or into the paths of motion of the needles *d* without endangering the efficiency of said needles, in this manner greatly increasing the output of the machine.

The method of attaching or securing the leather or other covering *c* over the lower edge of the lip *a* may be carried out in many ways; but the method we preferably follow is by making the lip *a* detachable and not forming it integrally with the nipper-knife *b*. By these means we are enabled to wrap the leather around the lip *a* and secure one of its loose ends between it and the face of the nipper-knife *b* by firmly attaching the lip *a* thereto by the screws *g*, while the other loose end is secured by the strip *y*.

Instead of covering the lip *a* with the substance or material suitable for holding the fibers, as well as for being cut through by the points of the needles, as above described, we might make or produce the whole of said detachable lip *a* of some such suitable substance, as, for example, vulcanite, wood fiber, compressed papier-mâché, or the like, and thus attain the object of our invention. However, we preferably make use of the method first before described.

We claim—

1. A combing-machine having the lip of the nipper-knife extended into close proximity to

the path of travel of the combing-needles, the lower edge of the lip being non-metallic to prevent injury to the points of needles that may contact therewith.

- 5 2. A combing-machine having its nipper-knife provided with a detachable lip having a non-metallic lower edge extended into close proximity to the path of travel of the combing-needles.
- 10 3. A combing-machine having its nipper-knife provided with a detachable lip, said lip

having a wrapping of relatively soft material the lower portion of which is extended into close proximity to the path of travel of the combing-needles.

In testimony whereof we have affixed our signatures in presence of two witnesses.

CHARLES FREDERIC AINSWORTH.
SYLVANUS ANDERTON.
